MOLDED BUTTER PATTY OR THE LIKE

Leo Peters, 750 Plymouth Road SE,
Grand Rapids, Mich.

Filed Apr. 2, 1964, Ser. No. 79,310

Term of patent 14 years

(Cl. D82—2)

FIG. 1

FIG. 3

FIG. 2

FIG. 4

FIG. 1 is a top plan view of a molded butter patty or the like, showing my new design;

FIG. 2 is an end view in elevation;

FIG. 3 is a side view in elevation; and

FIG. 4 is a bottom plan view.

I claim:

The ornamental design for a molded butter patty or the like, substantially as shown.
